Eli C. Townsend

UNITED STATES PATENT OFFICE.

ELI C. TOWNSEND, OF NEW YORK, N. Y., ASSIGNOR OF ONE-HALF TO
STEPHEN J. COX, OF SAME PLACE.

KEY-FASTENER.

SPECIFICATION forming part of Letters Patent No. 411,076, dated September 17, 1889.

Application filed October 8, 1888. Serial No. 287,504. (No model.)

To all whom it may concern:

Be it known that I, ELI C. TOWNSEND, a citizen of the United States, residing at New York city, in the county of New York and State of New York, have invented a new and useful Improvement in Escutcheons and Key-Protectors, of which the following is a specification, reference being had to the accompanying drawings, forming part of the same, in which similar letters refer to similar parts throughout the several views.

The object of my invention is to provide in an escutcheon a guard or shield against loss of key, or removal thereof from the lock, except at will of the operator. I attain these objects by the mechanism illustrated in the accompanying drawings, in which—

Figure 1 is a perspective view of my invention in position, exhibiting position of the key. Fig. 2 represents a slotted movable plate or disk containing subkey-hole H. Fig. 3 represents a stationary disk or plate with perforations for screws and key-hole proper H.

The plate B is held in position by placing the plate A within the raised perimeter K of the plate B, and inserting screws through the apertures A'. These screws pierce the slots B', and permanently fasten the two plates to the door or other object upon which the duplex escutcheon or plates may be placed. The screws are set in such a manner as to allow the plate B to rotate upon its center C the whole or any part of the distance between the ends of the slots B'. The slots B' may be made of any length essential to effect the

complete concealment of the subkey-hole H.

The key-holes in Figs. 2 and 3 are of the same size and shape, so that when placed one upon the other they will form one perfect duplex key-hole. The plate B, Fig. 2, being movable, and the plate A being rigidly held by the permanent screws A', a slight rotary movement of the raised perimeter K to the right or left effects the exposure of the subkey-hole H, or conceals the same and holds the key by its shank in the central position C, precluding the possibility of removing the same except by an opposite rotation of the raised perimeter K of the plate B, and thus effecting and affording at will the complete exposure and availability or entire concealment of the subkey-hole H.

What I claim as my invention, and desire to secure by Letters Patent, is—

A key-escutcheon consisting of two concentric circular plates with corresponding key-holes, the openings for the axial line of the key being placed in the center of the plates, the superimposed plate being permanently fixed, while the subjacent plate is capable of a limited rotation around the axial line of the key-shank by means of its projecting raised rim, and by the rotation of the subjacent plate the key-hole is occluded and the key securely held in place, substantially as set forth and described.

ELI C. TOWNSEND.
